UNITED STATES PATENT OFFICE

123,451

DESIGN FOR A WALLPAPER

Curt Oscar Hesse, New York, N. Y.

Application October 5, 1940, Serial No. 95,655

Term of patent 3½ years

To all whom it may concern:

Be it known that I, Curt Oscar Hesse, a citizen of the United States of America, residing in New York city, county of New York, and State of New York, have invented a new, original, and ornamental Design for a Wallpaper, of which the following is a specification, reference being had to the accompanying drawing, forming part thereof, wherein the figure of the drawing is a plan view of a wallpaper showing my design.

I claim:

The ornamental design for a wallpaper, substantially as shown.

CURT OSCAR HESSE.
